MACHINE FOR GILDING CARDS.

No. 290,303.

Patented Dec. 18, 1883.

UNITED STATES PATENT OFFICE.

CHARLES A. WRIGHT, OF PHILADELPHIA, PENNSYLVANIA.

MACHINE FOR GILDING CARDS.

SPECIFICATION forming part of Letters Patent No. 290,303, dated December 18, 1883.

Application filed October 20, 1883. (No model.)

To all whom it may concern:

Be it known that I, CHARLES A. WRIGHT, of the city of Philadelphia, county of Philadelphia, and State of Pennsylvania, have invented an Improvement in Machines for Gilding Cards, &c., of which the following is a specification.

My invention has reference to machines for gilding cards, paper, &c.; and it consists in a wheel loosely supported on a stationary bearing, and having its periphery provided with a series of clamps, by which the cards are clamped, and in many details of construction, all of which are fully set forth in the following specification and shown in the accompanying drawings, which form part thereof.

Heretofore it has been customary to clamp the cards, &c., in separate stationary benches, which required much space and the employment of much needless labor, rendering the process of gilding expensive and slow.

The object of my invention is to overcome these difficulties and objectionable features in the old method of gilding by providing suitable mechanism which takes up but little space, allows of rapid manipulation, and increases the production of work with the employment of less labor. With my improved gilding-wheel I am enabled to have as many as twenty-eight or thirty clamps in the space formerly required for two or three, and I am also enabled to work rapidly, as it is not necessary to shift about for every clamp, as they are successively brought before the gilder without his moving from one position. The advantage of this form of gilding apparatus is especially obvious in gilding the oblique edges of cards, as pointed out hereinafter.

In the drawings, Figure 1 is a side elevation of my improved gilding-wheel, showing all but three sets of clamps removed. Fig. 2 is a sectional plan view of same on line *x x*, and Fig. 3 is an enlarged side elevation of one of the clamps.

A is the stationary shaft. B is the clamp-wheel, and is loosely carried thereon, and is provided with lugs C, to support the clamps G from displacement. The shaft A is supported by a frame or support, D, and the wheel B is prevented from displacement by collars E F, secured to said shaft. If desired, the wheel B

may be secured to the shaft A and the latter supported in frames D, made integral with the collars E F; but I prefer the former construction, as I am enabled to place a number of the wheels B upon the same shaft and allow each to be rotated independently of the other.

The clamps G consist of two jaws, H and K, the former of which is clamped to the wheel B by bolts I and kept from displacement by two or four lugs, C. In place of these lugs, another bolt may be used. The lower jaw, H, is provided with forked prongs h, to support the board R, and the jaw K is provided with a cross clamping-piece, k, which presses down upon the board R'. The cards or paper S are clamped between the boards R R'. The jaw K is hinged to the jaw H at J, and is provided with an arm, K', which, during the rotation of the wheel B, moves against a stationary roller, L, journaled on the end of a spring-arm, P, secured to the rigid arm F' of the collar F or frame D; or it may be secured to the floor. If the clamping-pressure is removed, when the wheel B is turned so as to bring one of the extending arms K' against the spring-wheel L, the upper or hinged jaw, K, is forced away from jaw H, unclamping the cards. These jaws are clamped in the following manner: The jaw H is provided with a hub, M, through which a screw, N, works, which latter is provided with a hand-wheel, O, and bearing-point n, and is arranged to press down on the jaw K immediately below or belonging to the next clamp, G. By this construction the space between the jaws H and K is perfectly free and unobstructed, to allow of them clamping long panel-cards. Any other form of clamping mechanism may be used, if desired.

For ordinary use, the jaws H and K may be of the same length; but when the machine is to be used for gilding beveled-edge cards, as shown, the jaw K is considerably shorter than the jaw H, so as to correspond to the bevel on the card.

The joint J between the jaws H and K, being below the clamping-line of jaw K, causes the end k to clamp in a line tangent to the arc described about the said joint J, or in a direction toward the end of jaw H, as indicated by dotted line, Fig. 3, thereby insuring the oblique edges of the cards to be gilded being

pressed firmly together. A pivoted bar, U, supported on the floor at U', and provided at the top with a notch, u, may be used to hold the wheel B in a stationary position and in the right place during the gilding operation. The end of the jaw H rests in the notch, as shown.

The operation is as follows: The clamps are all furnished with cut cards, and then those of each clamp are gilded in succession, and when the cards are all gilded the wheels O are turned and the spring-wheel L forces up the jaw K, and the cards are removed and replaced by ungilded ones, and the operation takes place again.

I do not limit myself to the details of construction, as my invention comprehends, broadly, a gilding-wheel provided with a series of clamps upon its periphery; but I prefer the construction shown as being most practical.

Having now described my invention, what I claim as new, and desire to secure by Letters Patent, is—

1. A gilding-wheel formed of a wheel provided on its periphery or circumference with a series of clamps, the jaws of which clamp in lines radiating substantially from a point within the said supporting-wheel outward, substantially as and for the purpose specified.
2. A gilding-wheel formed of a wheel provided on its periphery or circumference with a series of clamps formed of pivoted jaws, and one or more of their clamping-edges being exposed to allow of manipulation of the object clamped, having independent clamping devices, by which each clamp may be opened separately, substantially as and for the purpose specified.
3. A gilding-wheel formed of a wheel provided on its periphery or circumference with a series of clamps having independent clamping devices, by which each clamp may be opened separately, and a spring device to open said clamps when released, substantially as and for the purpose specified.

4. A gilding-wheel formed of a wheel provided on its periphery or circumference with a series of detachable clamps, one or more of their clamping-edges being exposed, to allow of manipulation of the object clamped, substantially as and for the purpose specified.

5. A gilding-wheel formed of a wheel provided on its periphery or circumference with a series of clamps, the upper and lower jaws of which are of different lengths, substantially as and for the purpose specified.

6. A gilding-wheel formed of a wheel provided on its periphery or circumference with a series of clamps, the upper and lower jaws of which are of different lengths, and the pivotal point of the upper jaw being below its clamping-face, to obtain an outwardly-directed clamping action, substantially as and for the purpose specified.

7. A gilding-wheel formed of a wheel provided on its periphery or circumference with

a series of clamps, in combination with an adjustable support to arrest the clamping-jaws at a uniform height, substantially as and for the purpose specified.

8. A gilding-wheel formed of a wheel provided on its periphery or circumference with a series of clamps having independent clamping devices, by which each clamp may be opened separately, in combination with an adjustable support to arrest the clamping-jaws at a uniform height, substantially as and for the purpose specified.

9. A gilding-wheel formed of a wheel provided on its periphery or circumference with a series of clamps having independent clamping devices, by which each clamp may be opened separately, and a spring device to open said clamps when released, in combination with an adjustable support to arrest the clamping-jaws at a uniform height, substantially as and for the purpose specified.

10. A gilding-wheel formed of a wheel provided on its periphery or circumference with a series of clamps, the upper and lower jaws of which are of different lengths, in combination with an adjustable support to arrest the clamping-jaws at a uniform height, substantially as and for the purpose specified.

11. A gilding-wheel formed of a wheel provided on its periphery or circumference with a series of clamps, the upper and lower jaws of which are of different lengths, and the pivotal point of the upper jaw being below its clamping-face, to obtain an outwardly-directed clamping action, in combination with an adjustable support to arrest the clamping-jaws at a uniform height, substantially as and for the purpose specified.

12. A gilding-wheel formed of a wheel provided on its periphery or circumference with a series of clamps having independent clamping devices, by which each clamp may be opened separately, and the pivotal point of the upper jaw being below its clamping-face, to obtain an outwardly-directed clamping action, substantially as and for the purpose specified.

13. A gilding-wheel formed of a wheel provided on its periphery or circumference with a series of clamps having independent clamping devices, by which each clamp may be opened separately, the upper and lower jaws of which are of different lengths, and the pivotal point of the upper jaw being below its clamping-face, to obtain an outwardly-directed clamping action, substantially as and for the purpose specified.

14. A gilding-wheel formed of a wheel provided on its periphery or circumference with a series of clamps having independent clamping devices, by which each clamp may be opened separately, and a spring device to open said clamps when released, and the pivotal point of the upper jaw being below its clamping-face, to obtain an outwardly-directed clamping action, substantially as and for the purpose specified.

15. A gilding-wheel formed of a wheel pro-

- vided on its periphery or circumference with a series of clamps having independent clamping devices, by which each clamp may be opened separately, and a spring device to open said 5 clamps when released, the upper and lower jaws of which are of different lengths, and the pivotal point of the upper jaw being below its clamping-face, to obtain an outwardly-directed clamping action, substantially as and for the 10 purpose specified.
16. The combination of shaft A, supports D, wheel B, and clamping-jaws G, bolted or secured to said wheel, substantially as and for the purpose specified.
- 15 17. The combination of wheel B with rigid jaw H, hinged jaw K, and screw N, having wheel O, substantially as and for the purpose specified.
18. The combination of wheel B with rigid 20 jaw H, hinged jaw K, of shorter length than jaw H, and screw N, having wheel O, substantially as and for the purpose specified.
19. The combination of wheel B with rigid
- jaw H, having prongs h, hinged jaw K, of shorter length than jaw H, and having clamp- 25 edge k, and screw N, having wheel O, substantially as and for the purpose specified.
20. The combination of wheel B with rigid jaw H, hinged jaw K, having arm K', roller L, spring P, and screw N, having wheel O, 30 substantially as and for the purpose specified.
21. The combination of long rigid jaw H and short hinged jaw K, being hinged below its clamping-line, and devices to draw said jaws together, substantially as and for the purpose 35 specified.
22. The combination of wheel B with rigid jaw H, hinged jaw K, screw N, having wheel O, and wooden blocks R R', substantially as and for the purpose specified. 40

In testimony of which invention I hereunto set my hand.
